UNITED STATES PATENT OFFICE.

CARL SCHWARZ, OF PITTSBURGH, PENNSYLVANIA.

EXTENSION TOWER.

Application filed June 23, 1922. Serial No. 570,441.

To all whom it may concern:

Be it known that I, CARL SCHWARZ, a citizen of the United States, and a resident of Pittsburgh, in the county of Allegheny and the State of Pennsylvania, have made a new and useful invention in Extension Towers, of which the following is a specification.

This invention relates to extension towers.

In the distribution of material such as concrete in building operations, it is now customary to erect towers of sufficient height from the top of which to distribute the concrete throughout the entire building operations. These towers are generally of more or less skeleton formation built from heavy timbers and when the building operation is completed, the lumber entering into the make-up of the towers is practically lost or worthless. The construction of these timber towers is expensive, both from the standpoint of the lumber used and the labor necessary to build the same.

An object of this invention is to provide a tower capable of being used as the present towers are, (especially for concrete distribution) the major part of which is a permanent structure, capable of being collapsed for storage and transportation and of being extended to form the basis for a rigid and practical structure, capable of fulfilling all the requirements which such a tower has to meet.

This, as well as other objects which will readily appear to those skilled in this particular art, I attain by means of the device described in the specification and illustrated in the drawings accompanying and forming part of this application.

In the drawings, Figure 1 is a view in side elevation of a tower embodying this invention shown in extended or operative position. Figure 2 is a view in sectional front or back elevation as the case may be of the upper portion of the tower shown in Fig. 1. Fig. 3 is a top plan view taken on line 3—3 of Fig. 2. Fig. 4 is a view in side elevation of the tower shown in Fig. 1, collapsed with the elevator rails and tie rods removed. Fig. 5 is a top view in section of the top of the structure. Fig. 6 is a view partially in section and partially in plan taken on line 6—6 of Fig. 1, looking downward. Figs. 7, 8, and 9 are enlarged detail views of portions of the apparatus.

The tower in a general way consists of four series of lazy tongs so arranged and

articulated as to form a hollow square open-work structure capable of being manipulated from the base end thereof, so as to extend the same to the desired height and to collapse the same for the purpose of storing the structure or transporting it.

The structure is mounted upon a base and when extended to the desired height, is guyed against side movement and then formed into a rigid non-collapsing structure by means of horizontal tie rods and upright vertical rails forming elevator guides.

Each series of lazy tongs is made up of crossed levers 10 (shown in Fig. 9), each consisting of a bar-shaped body portion 11 having reinforcing ribs 12 and 13. The ribs are spaced at the center of the bar so as to allow the crossed bars to be riveted together as shown at 13 and the ends of the body portion are provided with holes or openings 14.

The co-operating series of lazy tongs forming the several sections of the structure are secured to corner brackets 15 illustrated in detail in Fig. 8. The ends of the bars 10 are preferably riveted to the corner brackets by means of shouldered rivets so that the bars can freely pivot in the brackets. Each pair of levers 10 for one side of a horizontal section of the structure are arranged so that the strengthening ribs 12 and 13 of one lever lie on the inside of the structure while those of the other lever lie on the outside of the structure.

The lower ends of the lowermost pair of crossed levers are pivotally connected to collapsible sill members 16—16 which in turn, rest on sills 17—17.

Two operating screws 18—18 each provided on opposite sides of its center with oppositely arranged threads at its center is unthreaded and the unthreaded portion of each is mounted for rotation in a supporting bracket 19 carried on its sill 17. Screws 18 are threaded through threaded blocks 20 secured in the ends of sill members 16. The outer end of each screw 18 carries a worm wheel 21 and an operating shaft 22 carrying an operating crank 23 at one end is provided with worms 24—24 which mesh with worm wheels 21. Shaft 22 is collapsible and the co-operating parts are preferably squared one externally and the other internally, so that both parts will operate in unison and as one in driving worms 24.

Sill members 16 which are collapsible, are preferably formed as shown in Fig. 7 which is a view taken on line 7-7 of Fig. 6 looking in the direction of the arrows. 5 One half of each member consists of a channel section 25 having a cover plate 26 closing its open side. Within this, a channel section 27 is fitted to slide. Channel 27 is provided with an end or abutment plate 28 10 and between this and block 20 two coil springs 29 and 30 are confined. Cover plate 26 is provided with an abutment end 31 which fits within channel section 27 and forms one abutment for two coil springs 29 and 30. The opposite ends of these springs abut against end blocks 20. 15 Sills 17 are supported on stationary foundation sills 32. As sills 16 are moved 20 toward one another by means of screws 18, sills 17 will be caused to approach one another by the series of lazy tongs which connect the same together and to sills 16; this occurs when the tower is extended. When 25 the tower is collapsed by reverse movement of screws 18, sill members 16 will be forced apart by the screws and sills 17 will be forced apart by the springs 29 and 30, as well as by the interconnected lazy tongs. 30 The four series of lazy tongs at their top support the tower head and the four members 33 making up this head are each formed in substantially the same manner as one of 35 the sill members 16. Each member 33 at its outer end carries a block 34 formed with an eye 35 for a guy wire or cable. The block is held in the end of the channel member forming one portion of member 33, by a rivet 36 which passes through the channel 40 member, the block 34, and an end plate 37 with which inner channel member 38 of member 33 is provided. By this means, the four members 33 are held in proper relation to form a square having collapsible sides. 45 After the tower is extended to the desired height, horizontal connecting bars 39 are hooked in place in holes 40 formed for that purpose in brackets 15 and by means of turn-buckles 41 these horizontal connecting

members are tightened up so as to stiffen the structure. The elevator rails 42 are next positioned and bolted in place to the levers 10. The opening between stiffening ribs 12 and 13 on the inner levers 10 is of such 55 length as to accommodate the elevator rails.

The springs confined within top members 33 are preferably of such length that they will not contact with their abutments when the tower is collapsed, nor until it has 60 reached about half of its extended height. If desired, this may also be true of springs 29 and 30 forming part of sill members 16.

An elevator or cage 43 is adapted to slide 65 within elevator guides 42 and to be operated by means of a suitable cable 44 which passes over pulleys 45 and 46 carried on cat-head 47.

While I have described but one embodiment of my invention, it will be apparent 70 that various changes, modifications, additions and omissions may be made in the apparatus illustrated without departing from the spirit and scope of the invention as set forth by the appended claims.

I claim:

1. In an extensible tower, a multiple series 80 of interconnected co-operating lazy tongs forming a hollow extensible structure, threaded rods for operating said lazy tongs, a worm wheel on each rod and a telescoping worm shaft for driving said worm wheels.

2. In an extensible tower, four series of 85 interconnected co-operating lazy tongs forming a rectangular extensible structure, a rectilinearly expandible tower head secured to said tongs and means for raising and lowering the structure.

3. In an extensible tower, a multiple 90 series of interconnected co-operating lazy tongs forming a hollow extensible structure, threaded rods for operating said lazy tongs, a worm wheel on each rod and an extensible worm shaft for driving said 95 worm wheels.

As testimony whereof, I have hereunto 100 subscribed my name this 15th day of June, 1922.

CARL SCHWARZ.
